SOAP STOCK AND PROCESS OF MAKING

Benjamin H. Thurman, Bronxville, N. Y., assignor
to Refining, Inc., Reno, Nev., a corporation of
Nevada

Application March 19, 1938, Serial No. 196,977

7 Claims. (Cl. 260—425)

This invention relates to soap stock and process of making, and more particularly to a process of refining vegetable oils so as to produce an improved soap stock while reducing refining losses and also producing an improved raw oil as an intermediate product in the process.

The soap stock now produced in refining vegetable oils contains large amounts of impurities, such as phosphatides, proteins and other non-fatty material. It is extremely difficult to purify such soap stock so that it may be incorporated into commercially acceptable soaps or otherwise used. According to Lewkowitsch the average composition of cottonseed soap stock is as follows:

	Percent
Fatty anhydrides	48.50
Glycerine	3.98
Caustic soda (Na ₂ O)	3.20
Foreign organic matter	5.90
Water	36.00
Coloring matter	2.42
	100.00

Such a mixture cannot be kept in storage for any length of time or shipped without fermentation and decomposition. It has heretofore been attempted to use this material by subjecting it to washing and graining out processes similar to those used in the conventional kettle soap making processes. Such processes are expensive and time consuming, as several washes are usually employed along with the addition of more alkali in order to completely saponify the mixture. The material is very dark in color, as much of the "foreign organic matter" is also highly colored in addition to that listed above as "coloring matter." According to Thomssen & Kemp's "Modern Soap Making," approximately 1000 pounds of soap stock having a 50% fatty acid content, 100 pounds of solid, 76% caustic soda, and 100 pounds of salt are required to produce 750 pounds of settled soap.

As further stated by Thomssen & Kemp, the soap thus produced is soft bodied and has a characteristic and disagreeable odor. It is quickly soluble, but produces a thin, slimy lather. The use of such cottonseed soap stock is limited to soap powders and similar preparations. Such products seldom contain more than 25% soap, as large amounts of soda ash and other filling materials are used to disguise the odor, hide the color and serve to preserve the soap. Little, if any, bar soap is made from soap stock at the present time.

Soap stock is, in many cases, treated with sulfuric acid, to decompose the soap and liberate fatty acids, and also is treated with splitting reagents, such as Twitchell reagents, to split any glycerides present to further liberate fatty acids. The liberated fatty acids are then distilled, leaving a residue containing a large percentage of the fats. This residue is like tar or pitch and is useless waste material. In addition, some of the impurities distill over with the fatty acids, which necessitates at least a second distillation to produce fatty acids of sufficient purity for making commercially acceptable soap. This also is an expensive and time consuming proposition and results in wasting a large percentage of the soap stock.

In accordance with the present invention, oils such as cottonseed, soya bean, corn, rapeseed and linseed, are refined by a process which produces a soap stock substantially free of odorous impurities and those which readily ferment and decompose, at the same time the refining losses are reduced markedly over those occasioned in conventional refining processes. Also, an improved raw oil is produced as an intermediate product which, if drying oils, such as linseed or soya bean, are being refined, may be sold as a semi-refined or "non-break" raw oil. Minor constituents which constitute deleterious impurities in the soap stock are recovered separately from the soap stock, and since these minor constituents from most vegetable oils contain large percentages of phosphatides, the material thus recovered can be used as such as a phosphatide material or may be readily purified by a simple process to produce relatively pure phosphatides.

It is, therefore, an object of the invention to provide an improved refining process for vegetable oils by which a relatively pure soap stock capable of being directly incorporated into high quality soaps is produced.

Another object of the invention is to provide a process of refining vegetable oils in which phosphatides are recovered as a valuable by-product separately from the soap stock.

Another object of the invention is to provide a process of refining vegetable oils in which oils having "non-break" characteristics may be produced.

Another object of the invention is to provide a new and improved soap stock product.

In carrying out the present invention, the vegetable oils being refined are subjected to a two-stage process. In the first stage, the odorous materials and those which readily decom-

pose and ferment, are substantially completely removed prior to contacting the oil with the usual alkali refining reagent. By employing a suitable precipitating reagent, substantially all of such materials can be removed in a single operation so as to produce a "non-break" oil. That is, an oil in which no substantial darkening of the oil or precipitation of foots will take place if the oil is heated to 600° F. Also, by employing a precipitating reagent which has preservative properties, the crude phosphatides thus removed may be stabilized against fermentation and decomposition. The entire process is preferably carried out as a continuous operation.

Batch precipitation with either settling or centrifugal separation of impurities has heretofore been proposed, but large losses were occasioned therein and the percentage of precipitating reagent was critical. Also by these suggested processes it was not possible to substantially completely remove the ingredients which result in fermentation and decomposition of the soap stock produced by subsequent refining. Furthermore, the thus purified oil was difficult to refine as the long time of heating in the batch mixing process tended to set the colors in the oil. Batch refining of oil resulting from either batch or continuous precipitation and separation treatment is not practicable, as the soap stock settled from the oil entrains large amounts of neutral oil, thus producing excessive refining losses. Such soap stock is a loose flocculated material because of the reduction of the amount of non-fatty impurities therein and will not settle compactly from the refined oil.

In accordance with the present invention, the oil is substantially completely denuded of the constituents which are deleterious in the soap stock. This is done in a continuous operation effected in a very few minutes such that the oil is not subjected to lengthy heating. The colors are not set and, if desired, sufficient of the constituents are removed so as to produce, prior to complete refining, an improved oil having non-breaking characteristics. The treated oil may then be substantially immediately contacted with an alkaline refining reagent as part of the same continuous process and quickly thereafter centrifuged to separate the soap stock from the refined oil. The heated oil from the precipitation and separation operations is preferably utilized promptly in the alkali refining operation so that the oil is not subjected to two separate heating operations. It is advantageous to maintain the oil out of contact with the air while in a heated condition, and therefore, the present invention contemplates employing a closed system from the point of entrance of the oil into the precipitating step to its discharge from the process as refined oil.

It is, therefore, an object of the invention to provide a continuous process of removing materials which constitute deleterious impurities in soap stock and then alkali refining vegetable oils.

Another object of the invention is to provide a rapid process of first removing phosphatide constituents and then the free fatty acids from vegetable oils in which the oil is maintained out of contact with the air during such process.

A further object of the invention is to produce a stabilized or preserved phosphatide material.

A still further object of the invention is to provide a continuous process of purifying and alkali refining vegetable oils by which the over-

5 all losses are reduced below that of known refining processes.

Other objects and advantages of the invention will appear in the following description of the invention, which is made in conjunction with the diagrammatic drawing of an apparatus suitable for carrying out the process and shown on the attached drawing.

10 Referring to the drawing, a source of supply for the oil to be treated is shown as 10. A source of supply for a phosphatide precipitating reagent is shown as a tank 11. Proportioning pumps 12 and 13 for oil and reagent, respectively, may be employed to withdraw oil and reagent 15 from the tanks 10 and 11, respectively, and deliver these materials through pipes 14 and 15 to a flow mixer 16. The proportioning pumps 12 and 13 may be driven by a variable speed motor 17 with a variable speed device 18 positioned 20 between the pumps so that any desired amounts and proportions of oil and reagent may be delivered to the mixer 16. The particular proportioning mechanism disclosed is shown merely by way of example, and any other suitable type of 25 proportioning device which will deliver proportioned streams of oil and reagent to the mixer 16 may be substituted therefor.

The mixer 16 may be any suitable flow mixer, such as a device in which a stream of one of the 30 materials is injected at right angles into the stream of the other, or may be any suitable mechanical agitator. The oil and reagent are thoroughly or intimately mixed in the mixer 16 and constituents, including phosphatides, proteins, 35 etc., are precipitated to render them capable of being centrifugally centrifuged from the oil. Such centrifugal separation can be more effectively carried out at elevated temperatures since a difficultly separable emulsion tends to form 40 when the oil and reagent are admixed. It is, therefore, desirable for effective separation that the mixture of oil and precipitated material be separated at an elevated temperature, and this temperature can be attained by preheating the 45 oil by passing the same through a heating device shown as a coil 19 positioned in a heating jacket 20 through which any desired heating medium, such as hot water, steam or heated oil, may be circulated by the pipes 21 and 22.

50 Alternatively, mixing can be performed at a relatively low temperature and the mixture heated by passing the same through a heating device shown as a coil 19' positioned in a heating jacket 20' through which any desired heating medium can be circulated by the pipes 21' and 22'. Also, both the heating devices 19 and 19' 55 can be employed, each furnishing part of the heat necessary for separation, or either one can be eliminated depending upon the type of oil being treated. In any case, the heated mixture is delivered through a pipe 23 to a continuous 60 centrifugal separator 24 from which the precipitated materials are discharged as a heavy effluent through the spout 25 into a receiver 26. The oil is discharged as a lighter effluent through a pipe 27. While the oil thus discharged may be conducted directly to the alkali refining treatment stage, it is sometimes desirable to provide 65 a small reservoir in order to insure a constant flow of materials through the alkali treatment operation even if small variations in flow occur in the discharge of oil from the centrifuge 24. Such a reservoir may be a closed tank 28 of 70 relatively small capacity. In order to prevent

contact of the heated oil from the centrifuge 24 with the atmosphere, the tank 28 may be provided with a water seal, for example, a closed tank 29 and an open tank 30. The tanks 29 and 30 may contain water or other sealing liquid and the tank 29 is connected to the tank 28 by a pipe 31 terminating above the surfaces of the liquids in these tanks, while the tank 30 may be connected to the tank 29 by a pipe 32 terminating below the surfaces of the liquid in the tanks 29 and 30. By such an arrangement, or its equivalent, the oil level in the tank 28 may vary without causing air to be drawn from the atmosphere into the tank 28. In many cases it is desirable to hold the tank 28 under vacuum to not only exclude air from contact with the oil but to also remove air which may be present in the oil. Also, with certain oils, the tank may be open to the atmosphere, in which cases the provision of such a seal is not necessary. If it is desired to withdraw the purified oil to be employed or sold, such oil can be withdrawn, for example, from the tank 28 through the pipe 33. Thus the present invention can be employed to produce a "non-break" drying oil which can be, if desired, further treated, for example, by vacuum drying, or washing and vacuum drying, in order to produce an acceptable commercial oil.

To remove the free fatty acids in the oil delivered to tank 28, this oil may be withdrawn by a proportioning pump 34 and delivered through a pipe 35 and heat exchange coil 34' provided with a casing 35' through which any desired heating or cooling medium may be circulated to a flow mixer 36. An alkali refining agent may be withdrawn from a source of supply 37 and delivered by proportioning pump 38 through a pipe 39 to the mixer 36. The proportioning pumps 34 and 38 may be of the same type as the proportioning pumps 12 and 13 and may also be driven by a variable speed motor 17 with a variable speed device 18 positioned between the pumps 34 and 38, or any other suitable proportioning mechanism for delivering accurately proportioned streams of oil and alkali to the mixer 36 may be employed. The mixer 36 may be similar to the mixer 16, thus, it may be a device for injecting a stream of one material into a flowing stream of the other, or it may be any suitable type of mechanical agitator. The alkali contacting the oil in the mixer 36 substantially instantaneously neutralizes the free fatty acids therein to form soap stock.

Since it may be desirable to separate the soap stock formed in the mixer 36 at a higher or lower temperature than the mixture coming from the mixer 36, a heat exchange device, shown as a coil 40 positioned in a jacket 41 through which any desired heating or cooling medium may be circulated by means of pipes 32 and 43, may be employed to adjust the temperature of the oil entering the continuous centrifugal separator 44 for continuously separating soap stock from refined oil. The soap stock is discharged as a heavy effluent from the centrifuge 44 through a spout 45 into a receiver 46, and refined oil is discharged as a lighter effluent through the pipe 47 into receiver 48.

It has heretofore been known that water alone or water containing very small amounts or traces of various reagents will precipitate impurities from vegetable oils. However, in general, water alone or water with such small amounts of reagents will precipitate only a very small por-

tion of the materials removed by the present process. In accordance with the present invention, precipitating reagents are employed in water solutions of sufficient concentration to substantially completely precipitate the constituents which cause "breaking" of the oil and give the soap stock deleterious properties. Boric acid is one preferred reagent, and applicant has found that a 10% solution of boric acid employed in proper proportions will precipitate substantially all of such constituents, although this concentration may be varied somewhat with different oils. The boric acid is a preservative for precipitated materials and is discharged in thorough admixture therewith from the centrifugal separator. The thorough admixture of the preservative with the separated material is important, since it is difficult to mix a preservative agent with this material after it has been separated, as it then is characterized by being a thick, viscous mass. The employment of boric acid also enables the subsequent employment of the separated constituents as phosphatides for edible purposes, either in the form in which they are discharged from the separator or after purification. Other reagents may be used for precipitating the phosphatides and non-fatty constituents from the oil and in general electrolytes which have no substantial deleterious reaction upon the oil being refined can be employed. Thus certain acids, alkalies and salts may be employed. Even strong mineral acids, such as sulfuric, may be employed if sufficiently dilute to prevent substantial destruction of the phosphatides as well as reaction with glycerides and fatty acids, all of which occurs in conventional acid refining with concentrated mineral acids. Other organic acids, such as acetic acid, may also be employed in approximately 10% concentrations. If strong alkalies, such as caustic soda or caustic potash, are employed they should be sufficiently dilute to prevent substantial attack upon and saponification of the neutral oil. Weak alkalies, such as sodium silicate, trisodium phosphate and triethanolamine, may be employed in approximately 10% concentration. In any case where alkalies or alkaline salts are used, the amount of reagent employed is insufficient to saponify any substantial quantities of the free fatty acids. Substantially neutral salts, such as sodium sulfate, sodium borate, sodium chloride and zinc chloride may also be employed in relatively concentrated solutions in order to throw the impurities out of the oil solution. Certain of these materials, for example sodium silicate and zinc chloride, also act as preservatives of the phosphatides. The reagent selected will depend upon the type of oil being treated and the contemplated subsequent use of the precipitated and separated materials.

In the batch processes referred to above, it was necessary to employ a very small quantity of the aqueous reagent in order to prevent substantial emulsification during agitation in the kettle. That is, the aqueous solution was used in quantities which would not wet the oil or produce a difficultly separable emulsion between the oil and water during the prolonged agitation necessary for adequate mixing. Since such prolonged agitation is not employed in the present process, it is possible and also extremely desirable to use considerably more precipitating reagent than could be employed in batch mixing steps. Thus, quantities ranging from 2 to 5 times greater than

that which would be normally used in the kettle or batch method are contemplated.

Hot vegetable oils containing free fatty acids will form large amounts of foam when mixed with air in the entrance and discharge passages of a centrifugal separator, thus interfering with separation, which was one of the difficulties encountered when attempts were made to centrifugally separate the material precipitated in a batch or kettle mixing step. The larger amounts of reagent of the present process sufficiently wet the oil to prevent the oil from foaming during centrifugal separation. Also, the larger amounts of reagent and the resultant wet mixtures are effective to materially reduce entrainment of free oil with the separated material so that losses are markedly reduced. Furthermore, such larger amounts of reagent soften the precipitate so that it will not adhere to the walls of the centrifugal bowl. This adherence of the precipitated material compels frequent cleaning of the bowl and results in ineffective separation in the prior processes referred to. In the present process, therefore, sufficient reagent should be employed to wet the oil so as to prevent foaming during centrifugal separation, prevent substantial entrainment of free oil in the precipitated material separated from the oil, and prevent adherence of the precipitated material to the walls of the centrifugal bowl.

An exact numerical amount of precipitating reagent which should be employed in the present process applicable to all oils can not be given, as the amount will vary with different oils, increasing with the amount of phosphatides and non-fatty constituents contained therein. The amount of these constituents apparently varies according to the amount of decomposition which has taken place in the seeds from which the oil is obtained. That is, in general, the amounts of these constituents increase with increase of free fatty acid content of the oil. For example, an oil containing 0.65% free fatty acids had a content of 1.28% of these constituents, while an oil containing 9.18% free fatty acids had a content of 3.40% of these constituents, and similar relationships with the free fatty acid content are generally found. Thus the free fatty acid content may be employed as a rough guide for determining the necessary percentage of precipitating reagent. For oils containing very small amounts of precipitable material, 1% of reagent may be sufficient, while other oils may require as much as 10%. In any event, the amount of precipitating reagent should be sufficient to precipitate the phosphatides and non-fatty matter and wet the oil as discussed in the previous paragraph.

The optimum temperature of separation will vary with different oils, but, in general, will lie between 100 and 160° F., although with some oils temperatures somewhat below this range may sometimes be employed. The important consideration is that the mixture be at an emulsion breaking temperature during centrifuging and for this reason it is possible to preheat the oil or both the oil and the precipitating reagent prior to admixture. Thus, a heating device similar to 19 can also be inserted in the pipe 15. Since, in such an operation, the oil is rapidly heated, and almost immediately thereafter separated from the resulting foots and then promptly alkali refined, no setting of the color in the oil is caused as is the case in batch processes involving pre-

heating. Also the precipitating reagent may be heated in the tank 11 before introducing the same into the process by any suitable heating arrangement, such as a heating coil or jacket (not shown). This step is of particular importance when the precipitating solution is substantially saturated at the temperatures employed in the process. For example, the 10% solution of boric acid above referred to must be kept at a temperature of approximately 150° F. to prevent crystallization of boric acid. By preheating both the oil and precipitating reagent and preventing the temperature from dropping below 150° F. during the precipitating operation, such crystallization can be prevented. With other precipitating reagents the temperature may be somewhat lower and subsequent heating employed instead of preheating.

As before stated, a portion of the constituents separated by the present process can be precipitated by the employment of water alone, but large amounts of them will remain in the oil so as to appear in the resulting soap stock and also cause the oil delivered from the centrifuge 24 to be a "break" oil. Since water is conventionally employed in the cooking operation prior to expressing vegetable and animal oils, a portion of these constituents are usually in an already precipitated state such that merely heating the oil and centrifuging the same will result in the separation of a portion thereof. In this case also large portions of these constituents remain in the oil from the centrifuge 24.

The preferred alkaline reagent for neutralizing the free fatty acids is an aqueous solution of caustic soda, but other alkalies, such as caustic potash, sodium carbonate, trisodium phosphate, etc., may be substituted therefor. The alkaline refining reagents are employed in amounts sufficient to completely neutralize the free fatty acids and ordinarily provide an excess for reaction with any minor constituents which remain in the oil. The excess will also cause removal of coloring matter with the soap stock if caustic alkalies are employed. The amount and concentration of alkali refining reagents added to the oil will vary with the free fatty acid content thereof and the type of oil being refined, and no precise proportions can be given. The concentrations known to be suitable for refining a given oil will, in general, be found suitable, but a somewhat smaller excess can usually be employed, as the phosphatides and other minor constituents which also react with alkalies have been previously removed. There is thus less opportunity for the saponification of neutral oil, resulting in lower losses. Also a saponification and entrainment inhibitor such as ethyl or isopropyl alcohol may be employed with the refining reagent as disclosed in the copending application of Benjamin Clayton, Serial No. 135,143, filed April 5, 1937.

The soap stock formed by reaction between the free fatty acids and the oil is separated in the continuous centrifugal separator 44 at an emulsion breaking temperature, since the addition of the aqueous refining reagent to the oil tends to form an emulsion. Either coil 34' or 40 or both may be employed to furnish any additional heat which may be necessary to provide such temperature and if desired a similar coil may be employed to preheat the refining reagent from the tank 37 in order to obtain a desired temperature of mixing. If the oil in tank 28 or delivered directly from the centrifuge 27 to the proportioning

pump 34 is at the requisite temperature so that a mixture with the refining reagent is produced in the mixer 36 at an emulsion breaking temperature, the heat exchange devices 34' and 40 may be eliminated, although in many cases it is desirable to provide a short time of contact between the alkali and oil prior to centrifugal separation in order to condition the soap stock for centrifugal separation. In the latter case, the coil 40 may be retained for that purpose, even if no heating or cooling is performed therein. If it is found advantageous to separate at a somewhat lower temperature than the temperature of mixing, the coil 40 may be employed to cool the mixture. With certain oils, it has been found desirable to employ the coil 34' to cool the oil to a temperature below that desirable for centrifugal separation, for example to 70 or 80° F., then mix the oil with the alkali and subsequently heat the mixture to an emulsion breaking temperature.

The emulsion breaking temperatures employed for centrifuging soap stock from the oil will vary with the type of oil being refined and the amount of free fatty acids therein, such that no precise temperature can be stated which is applicable to all oils. In general, this temperature will fall between 100 and 160° F., although in certain cases temperature somewhat above or below this range may be found desirable. The centrifugal devices employed may be of any suitable type capable of separating precipitated material or soap stock from animal and vegetable oils, but the heated centrifuges disclosed in the Patent No. 2,100,277 to Benjamin Clayton are preferred, as a more uniform discharge from the separators is produced thereby.

As previously stated, the soap stock formed by mixing an alkaline refining reagent with an oil containing free fatty acids but substantially no phosphatides or other non-fatty material can not be economically separated from the oil by a batch settling step, because of the entrainment of oil therein. However, the continuous centrifugal separation step of the present process has been found to effectively separate the oil from such soap stock without substantial entrainment of oil therein. In the process above described, the oil flows as a substantially continuous stream throughout the process, and sufficient movement of the mixtures, produced by adding either the precipitating reagent or refining reagent to the oil, is maintained to prevent stratification of the resulting froths from the oil prior to centrifuge, so that substantially uniform mixtures are delivered to the centrifugal separators. The entire process can be carried out within a few minutes, for example the oil and precipitating reagent can be mixed substantially instantaneously, or if agitators are employed, such agitation can be carried on for substantially less than five minutes. Centrifugal separation of the precipitate from the oil is a rapid process involving not more than two to four minutes. The oil may remain in the tank 28 for as short a time as two minutes, or if necessary, can remain in such tank for periods upwardly of fifteen to twenty minutes. The times of mixing, heating and centrifuging in the final refining operation may be substantially equivalent to those employed in the precipitating operation, such that the entire process may be carried out in as little as ten to fifteen minutes, although in certain cases with oils which are difficult to process, the time for the complete operation may extend as long as thirty minutes. Ap-

proximately the same time or a shorter time for the complete process is also possible where pre-heating of the oil or reagent, or both, is employed as above described. Since the oil is maintained in a heated condition for a short time only, the color is not set in the oils and no deterioration of the oil results. In general, a lighter colored oil is produced by the present process than by refining processes in which the free fatty acids and non-fatty materials are concurrently removed. Also, the maintenance of the oil out of contact with the air or substantially out of contact with the air during the entire process prevents deterioration of the oil.

As a specific example of the present process as compared with present day continuous refining processes, two samples of the same oil were treated in commercial size apparatus, the first sample being subjected to straight refining and the second sample being first treated to remove phosphatides and non-fatty matter and then refined under the same conditions as the first sample. The oil selected was a very good grade of cotton-seed oil containing only 0.64% free fatty acids and relatively a small amount (less than 1%) of phosphatides and non-fatty matter. Such an oil best illustrates the advantages of the process, as it is difficult to demonstrate an improvement over even conventional batch refining, as the losses are relatively small and a relatively good soap stock is produced in any event.

The first sample was refined by continuously mixing proportioned streams of oil and alkali at 75° F., the pressure in the mixing zone being 150 pounds per square inch. The amount of lye employed was 3.3% of 14° Bé. sodium hydroxide and the resultant mixture was passed through a series of three heating coils at 100°, 120° and 130° F., and then directly to the heated centrifuge above mentioned, in which steam was in contact with the bowl. Soap stock and a good grade of refined oil were continuously discharged as separate effluents. The refining loss in this process was 5.1% as compared with 6.04% obtained by the official cup test.

The second sample was subjected to the process of the present invention by preheating the oil to a temperature of 160° F. and then mixing the same with 1 1/2% of a 10% boric acid solution. The mixture was passed through two coils at a temperature of 150° F. and then the precipitated material separated from the oil in a heated centrifuge. The loss resulting from this portion of the process was 1.00%. The material separated from the oil contained a large percentage of phosphatides and substantially all of the boric acid solution, which acts as a preserving agent therefor. This material can be employed as a phosphatide material even in edible products, or can be easily purified to produce substantially pure phosphatides. The resultant oil was substantially free of phosphatides and non-fatty matter (less than 0.1%) and also had its free fatty acid content reduced to 0.48%. This oil was then cooled to 75° F. and refined in exactly the same manner and with the same proportions and concentration of alkali solution as the first sample. The refining loss in the refining step of the second sample was 3.3% which, added to the 1.00% loss in the first step, gives a total refining loss of 4.3% as compared to 5.1% refining loss for the continuous refining of the first sample and 6.04% by the official cup test.

The soap stock produced by continuous refining alone and by the present process had the following analysis and properties:

	Sample 1, soap stock from continuous refining	Sample 2, soap stock from present process
Water	Percent	Percent
Water	43.3	51.1
Free oil	18.8	15.8
Fatty acids	28.0	27.6
Sodium hydroxide	4.08	4.81
Phosphatides and nonfatty organic matter	5.82	0.69
Total	100.00	100.00
Nitrogen	0.195	0.065
Protein	1.22	0.41

	Sample 1	Sample 2
Physical characteristics of soap stock.	Viscous, pasty, brownish black mass; foul, putrefactive amine-like odor which becomes more pronounced on standing; ferments and putrefies rapidly.	Viscous, light brown mass; practically odorless; no foul or amine-like odor develops on standing.
Physical characteristics of soap produced.	Balls of soap, dark brown in color and having pungent amine-like odor which persists on standing.	Granular, light brown and odorless; no odor develops on standing.

It will be noted that the phosphatides and non-fatty organic matter present in the soap stock was reduced from 5.82% to 0.69%. As pointed out above, a high grade crude cottonseed oil containing only small amounts of phosphatides and non-fatty matter (less than 1%) was employed, such that the amount in even the soap stock from the straight refining process was relatively small. In general, the amount of phosphatides and non-fatty organic matter in the soap stock from straight refining will range from 5% to 10% or higher. Even with crude oils containing relatively large amounts of such materials, the present process produces soap stock containing only small amounts comparable to the 0.69% of the present example, i. e., soap stock containing less than 1% or at most 2%. Also, the minor constituents remaining in the soap stock of the present process are extremely stable, as shown by the non-odorous nature of such soap stock and the soap produced therefrom, and the absence of fermentation or putrefaction of the soap stock. The unstable non-fatty organic compounds were removed during the process. It will be further noted that the nitrogen content of the soap stock is greatly reduced, as is the protein content which was calculated from the nitrogen content. Nitrogenous compounds are, to a large degree, responsible for the foul odor, discoloration, and tendency toward putrefaction of ordinary soap stocks. It is evident that the small amount of nitrogenous compounds in the soap stock of the present invention is relatively stable.

The soap stock from both the straight refining process and the present process was converted into soap by adding sufficient sodium hydroxide solution to saponify the neutral oil present and heating. The soap was salted out and washed several times with water and then dried and powdered. The physical properties of the soap are given in the above table. It will be noted that the soap stock of the present invention produced a granular soap which was odorless and light brown in color, whereas the soap stock

from straight refining was not granular and had a dark brown color and pungent amine-like odor.

Thus the soap stock produced is substantially odorless and is of light color and can be converted into odorless light colored granular soap. Also the materials separated from the oil by the centrifuges 24 and 44 respectively contain reduced amounts of neutral oil, such that refining losses due to entrainment of neutral oil in the separated material is markedly reduced over conventional processes. The precipitating reagent is either of a nature which will not attack the neutral oil or is employed in sufficiently dilute concentration and amounts to prevent attack of the neutral oil. The oil from which the precipitated material has been separated can be treated with an alkaline refining solution by the continuous refining step and the neutral oil substantially completely separated from the resulting soap stock. Such oil can not, however, be economically refined by batch or kettle refining involving settling of the soap stock from the oil, since the settled soap stock entrains large amounts of free oil. The soap stock resulting from the present process is substantially free from fermentable and readily decomposable materials and can be incorporated directly into high quality soap products either in bar or powdered form in amounts of approximately 40 to 60% or greater. The soap product thus produced is substantially free of materials which will cause decomposition and deterioration of the soap.

The refined oil discharged from the centrifuge 44 may be treated with any conventional and well known clarification or bleaching step, such as washing and vacuum drying or treatment with absorbent clays and filtering, and such steps can be carried on as part of the continuous process. The process has been described in conjunction with vegetable oils, but is applicable to any type of glyceride or other fatty oils presenting the same problems.

While I have disclosed the preferred embodiments of my invention, it is understood that the details thereof may be varied within the scope of the following claims.

What I claim is:

1. The continuous process of treating vegetable oil containing phosphatides, non-fatty matter and free fatty acids, comprising the steps of, mixing a stream of an aqueous solution of a reagent which will precipitate said phosphatides and non-fatty matter with a stream of said oil in sufficient amount and concentration to substantially completely precipitate the same without destruction of said phosphatides or said oil, promptly continuously centrifugally separating the precipitated material from the oil, promptly mixing a stream of an alkaline refining reagent with a stream of the resultant oil in sufficient amount and concentration to substantially completely react with the fatty acids therein to form soap stock, and promptly thereafter centrifugally separating said soap stock from said oil to produce a substantially pure soap stock.

2. The continuous process of treating crude glyceride oil containing phosphatides and free fatty acids, comprising the steps of, mixing a stream of a precipitating reagent which will precipitate phosphatides without destruction of said phosphatides or said oil with a stream of said oil, promptly continuously centrifugally separating the precipitated phosphatides from the oil, promptly thereafter mixing a stream of an alkaline refining reagent with the separated oil

in sufficient amount to react with substantially all of said free fatty acids to form soap stock, and thereafter promptly continuously centrifugally separating said soap stock from said oil.

3. The continuous process of treating glyceride oils containing free fatty acids and non-fatty matter, which comprises the steps of, mixing a stream of an aqueous solution of a reagent which will precipitate said non-fatty matter with a stream of said oil in sufficient amount and concentration to precipitate substantially all of the non-fatty matter contained in the oil without destruction of said non-fatty matter or said oil, promptly continuously centrifugally separating the precipitated non-fatty matter from said oil, promptly mixing a stream of an aqueous alkaline solution with a stream of the resultant oil in sufficient amount to substantially completely neutralize said free fatty acids, and thereafter promptly continuously centrifugally separating the resulting soap stock from said oil.

4. The process of treating crude glyceride oils containing free fatty acids and minor constituents including phosphatides, which comprises the steps of, mixing an aqueous solution of a precipitating reagent in sufficient amount and concentration to precipitate substantially all of said minor constituents, promptly centrifugally separating the precipitated material from said oil while the same is in a heated condition, promptly thereafter mixing an alkaline refining reagent with the heated oil in sufficient amount to react with substantially all of the free fatty acids to form a soap stock substantially free from said minor constituents, and thereafter promptly separating said soap stock from said oil while the same is in said heated condition.

5. The process of treating crude vegetable oils containing free fatty acids and non-fatty material, which comprises, continuously mixing a stream of said oil with a stream of an aqueous precipitating solution so as to precipitate non-fatty material to render the same separable from said oil, promptly delivering the resulting mixture to a centrifugal separator and continuously separating the precipitated material from said oil at an emulsion breaking temperature so as to deliver separate streams of foots and heated oil from said separator, promptly thereafter mixing a

stream of alkaline refining reagent with said stream of heated oil in sufficient amount to substantially completely neutralize said free fatty acids to form soap stock, and promptly centrifugally separating said soap stock from said oil at an emulsion breaking temperature so as to produce separate streams of refined oil and soap stock substantially free of said non-fatty material.

6. The process of treating crude vegetable oils containing free fatty acid and non-fatty material, which comprises, continuously mixing a stream of said oil with a stream of a precipitating reagent so as to precipitate non-fatty material to render the same separable from said oil, promptly delivering the resulting mixture to a centrifugal separator and continuously separating the precipitated material from said oil at an emulsion breaking temperature so as to deliver separate streams of foots and heated oil from said separator, promptly thereafter mixing a stream of alkaline refining reagent with said stream of heated oil in sufficient amount to substantially completely neutralize said free fatty acids to form soap stock from said oil at an emulsion breaking temperature so as to produce separate streams of refined oil and soap stock substantially free of said non-fatty material, the process being carried out in a closed system whereby the oil is maintained out of contact with air while in admixture with said reagents and in a heated condition.

7. A quick and continuous process for treating vegetable oils containing gums, which comprises the steps of: continuously admixing a precipitating reagent of a character and amount sufficient to precipitate said gums but without substantially reacting with the free fatty acids contained therein; promptly, before injury to the oil, continuously centrifugally separating the precipitated gums from said oil; promptly continuously mixing a neutralizing reagent with the thus degummed oil in sufficient amount to substantially completely neutralize the free fatty acids remaining therein and to form foots and promptly continuously centrifugally separating the foots from the thus refined oil.

BENJAMIN H. THURMAN.
